JAR

Bruce L. Roberts, Rossford, Ohio, assignor to Owens-Illinois Glass Company, a corporation of Ohio

Filed May 4, 1964, Ser. No. 79,805

Term of patent 14 years

(Cl. D58—25)

FIG. 1

The dominant features of my design reside in portions shown in full lines.

I claim:

The ornamental design for a jar, substantially as shown and described.
